UNITED STATES PATENT OFFICE.

MINOTT W. SEWALL, OF ROSELLE, NEW JERSEY, ASSIGNOR TO THE BABCOCK & WILCOX COMPANY, OF BAYONNE, NEW JERSEY. A CORPORATION OF NEW JERSEY.

STEAM-BOILER.

986,090.

Specification of Letters Patent. Patented Mar. 7, 1911.

Original application filed June 12, 1909. Serial No. 501,751. Divided and this application filed August 18, 1910. Serial No. 577,480.

To all whom it may concern:

Be it known that I, MINOTT W. SEWALL, a citizen of the United States, residing at Roselle, in the county of Union and State 5 of New Jersey, have invented certain new and useful Improvements in Steam-Boilers, of which the following is a specification, the present application being a division of my application, Serial Number 501,751, filed 10 June 12, 1909, for steam-boilers.

The object of this invention is to produce a water tube steam boiler having the essential features of the inclined type of water tube boiler, as regards position of tubes, position of headers and circulation of water and steam, which can be built at a reduced cost.

The circulation of water in an inclined tube boiler is upwardly through the inclined tubes and the uptake manifolds to a horizontal drum or horizontal circulating tubes, through such drum or circulating tubes to the opposite end of the boiler and down through the connections between the horizontal circulating tubes or drums to the 20 downtake manifolds, and thence into the inclined water tubes. Such boilers are usually formed of straight tubes expanded into substantially vertical sinuous headers, or into 25 water legs formed of stayed flat surfaces with suitable drum connections at their upper ends. There is placed opposite each tube end in the manifolds a handhold fitting for access to the tube ends, both for the expansion of the tubes in the headers and for the purpose of cleaning. To enable this type of boiler to be more economically built I provide large cylindrical manifolds for the insertion of the tube ends of such dimensions 30 that a man can enter the manifold itself through a manhole to perform the work of expansion from the interior. The use of a cylindrical tube sheet, that is the portion of the manifold in which the tube holes are 35 bored, compels the bending of the tube ends to such form as will permit them to enter the tube sheet radially. It is desirable in this class of boiler that a sufficient quantity of water be contained in the immediate vicinity of the water line so that an appreciable time may be required to cause a reasonable variation in the water line, in order that such variation may occur without danger 40 of burning the tubes forming the heating

surface of the boiler. To obtain this desirable water volume the downtake manifold is extended upwardly and made of a larger diameter than the manifold proper. By this means the necessity of the usual horizontal drums or cross drums, of the so-called horizontal and cross drum type of boiler, may be eliminated and the expense and complication of the system may be thereby reduced.

My invention will be understood by reference to the accompanying drawings in which—

Figure 1 is a side elevation of the boiler and its setting; Fig. 2 a transverse section on the plane of the line 2—2 looking toward the rear of the boiler; Fig. 3 a horizontal section on the plane of the line 3—3 of Fig. 2; Fig. 4 a horizontal section on the plane of the line 4—4 of Fig. 1; Fig. 5 a side elevation of a modification; Fig. 6 a transverse section on the plane of the line 6—6 of Fig. 5; and Fig. 7 a horizontal section on the plane of the line 7—7 of Fig. 5.

Similar reference numerals indicate similar parts in the several views.

Referring to the drawings, the numeral 1 designates the uptake manifold and 2 the 40 downtake manifold, the latter having an enlarged upward extension 3. The manifolds are connected by inclined water tubes 4 which form the heating surface of the 45 boiler, and by the substantially horizontal tubes 5 and the tube 5^a which connect the upper end of the uptake manifold with the 50 upward extension 3 of the downtake manifold.

In Figs. 1, 2 and 4 I have shown superheating tubes 6 having manifolds 7, 8, 9 and 10. The manifold 7 is connected to the extension 3 by a nipple 11, and 8 and 9 are connected together by nipple 12. The manifold 10 terminates at its upper end in a 55 steam flange 13.

The boiler is fired from a furnace 14 having a bridge wall 15, a combustion chamber 16, and a wall 17 for deflecting and mixing 60 the furnace gases, said wall 17 having openings 18 for the passage of the gases through it. The furnace and combustion chamber have a roof 19 extending rearwardly of the wall 17, the opening 20 in the rear of said 65 roof admitting the furnace gases to the boiler tubes 4. The diaphragm 22 extends 70 forwardly from the rear wall toward the

uptake manifold and forms with the roof 19 and the side walls of the furnace a pass 21 in which the lower tubes of the bank 4 are placed. The diaphragm 22 terminates a sufficient distance to the rear of manifold 1 to provide an opening 23 to admit the gases to the upper tubes of the bank 4, said opening extending for only a part of the width of the boiler, as shown in Fig. 4. 10 A vertical wall 25 extends from diaphragm 22 to a roof 24 formed of bricks laid on the top tubes of the bank. The roof 24 extends from manifold 1 rearwardly to manifold 2 forming with diaphragm 22 and vertical 15 wall 25 two passes 27 and 28 among the upper tubes of the bank. Pass 27 is connected with 21 by opening 23, and with 28 by the opening 29 at the rear of wall 25. A connection to a flue may be made through opening 30 from pass 28. By this arrangement three passes are obtained among the boiler tubes of approximately the length of the tubes, and approximately proportional in cross section to the gas volumes due to the 20 temperature in the different parts of the boiler.

At the front of the boiler between manifold 1 and the side walls are doors 31 for access to the interior of the setting for the 25 renewal of tubes and for cleaning the exterior of the heating surfaces. At the rear the wall is built from the floor line up to the roof 22 of the pass 21. Above this wall I provide doors 38 by which access may be 30 had to the tubes for cleaning and to the manifolds of the superheater tubes. As shown in the drawings the outer tubes are bent from the center line of the two manifolds to the extent that the spaces between 35 the side walls of the boiler are greater than the manifolds, and substantially filled with tubes. This space between the side walls and manifolds is both convenient for cleaning and the removing of tubes in case of repair. 40 The weight of the rear manifold is carried on beams 32 through the saddle 33, the bracket 34 serving not for carrying the weight but for stability of the structure. A semi-circular wall 37 protects the lower 45 end of the rear manifold and allows access to the lowest point of the manifold for a blow-off connection 39. The front manifold 1 is supported on the small structural frame 50 55 35 by means of the saddle 36.

As clearly shown in the drawings, a portion of each of the manifolds extends beyond the boiler setting and by so doing an economy in setting material and labor is obtained. The exposed portions of the manifolds will, however, be properly covered with suitable non-conducting material to prevent radiation of heat. In each manifold is a manhole 41 for entrance to the manifolds, the work of expanding the tubes 60 being done from the inside. A connection

40 will be provided for introducing the feed water into the rear manifold at a short distance below the water line, such line being through the center of the tubes 5. Connections will also be made for the other necessary auxiliaries for a steam boiler. 70

The boiler shown in Figs. 5, 6 and 7 is adapted to the usual forms of settings of furnaces used for inclined water tube boilers. One feature of the construction shown in this particular setting is that ample access for cleaning the exterior of the tubes may be had through the doors 31 at the front, and 38 at the rear, so that baffles 42 parallel to the tubes may be used with the 75 possibility of completely cleaning the tube surfaces. The manifolds may be supported in substantially the same manner as before described, although in the present instance I have shown the rear manifold of Fig. 5 as supported on a circular metal base 43 resting on suitably prepared foundations. The front manifold may rest on a metal base 80 properly supported on structural work so as to give access to the furnace front, or it may be suspended to a frame of structural work passing over the top of the manifold as in Fig. 5. 85

In the form shown in Fig. 5 the tubes 4 must enter the manifolds at right angles to their vertical axes and this requires that the tubes be bent in more than one plane. That is in the construction of Fig. 5 the general axis of each of the tubes extends at an angle other than a right angle to the axes 90 of the manifolds, while the tube itself enters the manifolds radially and at right angle to the axes of the manifolds. In Fig. 1, however, with the manifolds slightly inclined the tubes are bent only in one plane; 100 that is, with inclined manifolds the general axis of each tube extends at a right-angle to the axes of the manifolds and the tubes enter the manifolds radially. By 105 "substantially vertical," therefore, whether in the specification or claims, I desire to include the slightly inclined setting of the manifolds shown in Fig. 1. Both the uptake and downtime manifolds may be made of approximately the same length, and the 110 boiler may be supplied with a cross drum with tube connections between it and the vertical manifold, as is customary for cross drum boilers of the inclined water tube type, or a horizontal longitudinal drum may be 115 placed above the manifolds and suitably connected by nipples as in the horizontal longitudinal drum type of inclined water tube boilers. In fact these manifolds are 120 susceptible of adaptation to many of the usual forms of inclined water tube boilers now in the market. For the purpose of replacing or repairing tubes it is essential that 125 a vertical space 49 shall exist adjacent to each horizontal row of tubes 4 by making 130

alternate vertical spaces between the horizontal rows of tubes respectively greater and less than the diameter of a tube, as shown at 49 and 50 in Fig. 2.

5. The tube 5 connecting the steam spaces in the manifolds provides a direct passage for the steam to the steam drum and leaves the pipe 5 free for a water passage.

What I claim and desire to secure by Letters Patent of the United States is:—

1. A steam boiler having an inclined bank of tubes, an uptake manifold of uniform diameter throughout its length, a downtake manifold having an upper cylindrical section 15 of substantially greater diameter than the lower section, and a main steam outlet connected to the upper section of the downtake manifold, said tubes being bent at their ends and expanded into the uptake manifold and 20 the lower section of the downtake manifold.

2. A steam boiler comprising uptake and 25 downtake cylindrical inclined manifolds, heating tubes expanded into said manifolds, the ends of the tubes being bent so as to enter the manifolds radially and permitting thereby all of the tubes to be expanded into the tube sheet, of the manifolds in an inclined bank of substantially greater width than the 30 diameters of the manifolds.

3. A steam boiler having a bank of inclined heating tubes, manifolds each having a section of equal diameters adapted to receive the ends of the tubes, one of said manifolds having an upper section of greater diameter than the tube-receiving section, said bank of tubes being of greater width than the tube-receiving section.

4. A steam boiler comprising a bank of inclined heating tubes, uptake and downtake 40 manifolds, the latter having an inclined cylindrical section of uniform diameter, an upper section of greater diameter than the lower section, said heating tubes being expanded into the uptake manifold and the 45 lower section of the downtake manifold, and circulation tubes connecting the upper ends of the manifolds.

5. A steam boiler having a bank of inclined tubes arranged in vertical rows having 50 horizontal center distances of substantially twice a tube diameter, and horizontal rows having vertical center distances alternately greater and less than twice a tube diameter, the ends of said tubes being so bent as to enter radially the tube sheet of inclined manifolds cylindrical in form and of uniform diameter throughout at least the length of the tube sheets, and of a diameter substantially less than the width of the bank of 55 tubes.

6. A steam boiler comprising substantially 60 vertical uptake and downtake manifolds, inclined tubes connecting said manifolds, a baffle supported by the lower tubes and extending rearwardly from the uptake, a sec-

ond baffle extending forwardly from the downtake above a portion of the tubes, and a third baffle extending from the uptake to the downtake and supported on the tubes, a vertical wall disposed among the upper portion of the tubes and resting upon the middle baffle and extending rearwardly from the uptake.

7. A steam boiler comprising substantially 70 vertical uptake and downtake manifolds, inclined tubes connecting said manifolds, a baffle supported by the lower tubes and extending rearwardly from the uptake, a second baffle extending forwardly from the 75 downtake above a portion of the tubes, an opening in said second baffle extending a portion of the width of the boiler and located at the front ends of the tubes, a third baffle extending from the uptake to the downtake and supported on the tubes, a vertical wall 80 disposed among the upper portion of the tubes and resting upon the middle baffle and extending rearwardly from the uptake manifold and dividing the space between the middle and upper baffles into two passages 85 extending the length of the tubes, and said third baffle having an opening located in the rear of the uptake manifold to permit the 90 exit of the gases.

8. A steam boiler comprising substantially 95 vertical manifolds, inclined tubes connecting said manifolds, a baffle supported by lower tubes and extending from one manifold toward the other, a second baffle supported by intermediate tubes and extending from one 100 manifold to the other and having an opening therein, a third baffle supported by upper tubes and extending from one manifold to the other, and a vertical wall disposed among the upper tubes and resting upon the middle 105 baffle and extending in the same direction as the first-named baffle.

9. A steam boiler comprising substantially 110 vertical manifolds, inclined tubes connecting said manifolds, a baffle supported by lower tubes and extending from one manifold toward the other, a second baffle supported by intermediate tubes and extending from one 115 manifold to the other and having an opening therein, a third baffle supported by upper tubes and extending from one manifold to the other, a vertical wall disposed among the upper tubes and resting upon the middle baffle and extending in the same direction as the first-named baffle, said upper baffle 120 having an opening therein on the opposite side of the vertical baffle from the opening through the second baffle.

10. In a water tube boiler, two parallel 125 inclined cylindrical manifolds, a plurality of rows of inclined water tubes connecting said manifolds, the general axis of each of said tubes extending at a right-angle to the axis of each manifold and the tubes entering the manifolds radially.

11. In a water tube boiler, two parallel inclined cylindrical manifolds, one of said manifolds having an enlarged upward extension forming a steam and water chamber, 5 a plurality of rows of inclined water tubes connecting said manifolds, the general axis of each of said tubes extending at a right-angle to the axis of each manifold and the tubes entering the manifolds radially, and a pipe connecting said manifolds above the water line.

10 horizontal circulation tubes connecting the upper ends of the manifolds.

12. In a water tube boiler, two parallel inclined cylindrical manifolds, a plurality of

rows of inclined water tubes connecting said manifolds, the general axis of each of said tubes extending at a right-angle to the axis of each manifold and the tubes entering the manifolds radially, and a pipe connecting said manifolds above the water line.

In testimony whereof I have hereunto 15 signed my name in the presence of two subscribing witnesses.

MINOTT W. SEWALL.
